United States Patent Office

Des. 194,552
Patented Feb. 12, 1963

194,552

LUGGAGE LOCK OR SIMILAR ARTICLE

Charles S. Gehrie, Montclair, N.J., assignor to Presto
Lock Co., Garfield, N.J., a limited partnership

Filed May 23, 1961, Ser. No. 65,290

Term of patent 14 years

(Cl. D50—7)

FIG. 1

FIG. 2

FIG. 1 is a perspective view of a luggage lock or similar article embodying my new design; and

FIG. 2 is a side elevational view of the same.

The portions shown in broken lines are for illustrative purposes only.

I claim:

The ornamental design for a luggage lock or similar article, as shown and described.
